UNITED STATES PATENT OFFICE

110,803

DESIGN FOR A DUPLICATOR

Allan V. Ditty, Detroit, Mich., assignor to Rapidx Corporation, Detroit, Mich., a corporation of Michigan

Application June 20, 1938, Serial No. 77,939

Term of patent 7 years

To all whom it may concern:

Be it known that I, Allan V. Ditty, a citizen of the United States, residing at Detroit, in the county of Wayne and State of Michigan, have invented a new, original, and ornamental Design for Duplicators, of which the following is a specification, reference being had to the accompanying drawings, forming part thereof.

I claim:

The ornamental design for a duplicator, as shown.

ALLAN V. DITTY.
